PORTABLE OIL PUMP AND TANK

Michael A. Tabet, Norfolk, Va., assignor to Tabet Manufacturing Company, Incorporated, Norfolk, Va., a corporation of Virginia

Application February 6, 1946, Serial No. 645,762

4 Claims. (Cl. 184—1.5)

1

The present invention relates to the art of removing oil and sludge from the crank case of an internal combustion engine and more particularly pertains to apparatus for withdrawing the used lubricant and foreign matter therein through an existing opening in an internal combustion engine such as the orifice through which the measuring stick is normally inserted.

An object of the invention is to provide for the removal of oil and sludge from the lubricant holding case of an engine without creating a special opening in the crank case or associated parts of the engine and to remove the lubricating oil from an engine by withdrawing the liquid oil and sludge through an opening already existing in the engine assembly such as the orifice through which oil is introduced into the crank case.

Another object of the invention is to provide a pumping arrangement including a relatively small tube which may be introduced into the crank case to the lowest point therein through the opening which is provided for the measuring stick which indicates the level of the lubricant in the crank case.

A further object of the invention is to provide portable apparatus which may be readily moved from one motor vehicle to another for discharging the oil from the crank case of the engine and for removing the used lubricant through the measuring stick opening and delivering the oil into a tank forming a part of the portable mechanism.

Another object of the invention pertains to apparatus for quickly and effectively removing the lubricating oil and foreign material from the crank case without the necessity of altering any part of the internal combustion engine and without the necessity of removing a drain plug which is usually arranged in the lower part of the crank case.

Other objects and features of the invention will be more apparent as the present disclosure proceeds and upon consideration of the accompanying drawings and following detailed description wherein an exemplary embodiment of the invention is disclosed.

In the drawings:

Fig. 1 is a front elevational view of portable apparatus embodying the invention;

Fig. 2 is a sectional view of the tank showing the pumping mechanism in end elevation and taken on the line 2—2 of Fig. 1;

Fig. 3 is a perspective view of the pump and drive mechanism and showing the top portion of the tank;

2

Fig. 4 is a diagrammatic view illustrating the circuit arrangement for controlling the pump and the signalling system;

Fig. 5 is an enlarged sectional view of the female part of one of the separable couplings;

Fig. 6 is an enlarged elevational view of the male part of a quick change coupling;

Fig. 7 is a perspective view of a conventional engine showing the suction tube in an operative position in the crank case; and

Fig. 8 is a perspective view of the oil measuring stick.

The present invention is directed to apparatus for quickly removing the lubricating oil from the crank case of an internal combustion engine such as the motor of an automobile. The apparatus is adapted for use in servicing motor vehicles such as is customarily provided by a filling station or by a shop servicing a fleet of trucks, buses or the like. The apparatus is also adapted to the removal of oil from engines on board boats. One of the characteristic features of the apparatus is that of removing the oil from the crank case in a relatively short period of approximately a minute whereby the used oil may be removed and the crank case refilled with fresh lubricating oil in a relatively short period so that the motorist may again obtain use of the vehicle without the necessity of placing the car over a drain pit or on an elevating mechanism for the drainage of the oil from a crank case.

The invention further pertains to the removal of the crank case lubricant through an existing opening in the engine assembly or through an opening which the motor car manufacturer has provided in the motor such as the breather opening or the measuring stick opening. The invention is accordingly adaptable to all types of engines in that the crank case lubricant is withdrawn through the opening normally accommodating the stick or rod which is employed to indicate the level of the lubricant within the crank case.

Referring to the drawings, there is shown generally at 10 a tank which may be of any appropriate size and shape and in the illustrated embodiment is substantially square in cross section and is adapted to hold approximately thirty or thirty-five gallons of liquid. The tank is preferably of such capacity that it may be portable and conveniently shifted from one place to another by an attendant even when the tank is filled with liquid. It is for this purpose that the tank is supported by a plurality of wheels 12 which may be in the form of casters whereby

the direction of movement of the tank may be readily altered. The casters or wheels 12 may be of a type which may be rolled with a minimum of effort including anti-friction bearings and the peripheries of the wheels may be furnished with resilient material such as rubber or a composition which is not attacked by hydrocarbon materials. The tank assembly includes a handle 14 at the rear portion thereof which extends across the width of this receptacle. Thus the tank may be conveniently moved and guided to any desired position.

The tank is closed at the top by means of a top wall 16 and this top member provides a base for supporting the pumping mechanism hereinafter described. The rear wall 18 of the tank is preferably arranged transversely of the apparatus at a point short of the rear extremities of the side walls 21 as shown in Fig. 2. A recess 22 is accordingly provided between the side walls 21 at the rear portion of the tank. The top wall 16 is hermetically joined to the sides and end walls of the tank and is preferably formed of sheet metal of substantial thickness so as to support the pumping mechanism and the controls therefor on the top wall. The bottom 15 of the tank is provided with a drainage opening which is normally closed by any suitable means such as a removable threaded plug 19.

In the illustrated embodiment an inverted channel member 24 is mounted transversely of the tank and may be welded or otherwise secured to the top 16. The inverted channel member 24 provides a passage or open space thereunder for accommodating electrical conductors which lead to the motor and various control switches. Any type of pump may be employed for withdrawing the oil from the crank case of an internal combustion engine and in the apparatus illustrated a gear pump 26 of a well-known construction is employed. The pump 26 is rigidly mounted on the inverted channel member by a plurality of bolt and nut assemblies 27. The pump 26 is driven by means of an electric motor 28. The motor 28 is also mounted on the inverted channel member 24 by means of a plurality of leg screws 29. The shaft 35 of the pump may be directly connected to the shaft 31 of the motor by means of a coupling 32 which is preferably of the type to provide a driving connection between the two shafts even though there is some displacement in the axial alignment thereof. It will be apparent, however, that other types of driving connections may be employed between the pump and the motor shaft.

In carrying out the invention the oil and sludge are withdrawn from the crank case of the engine by the pump 26 and delivered into the tank 10. Accordingly, the discharge opening 34 of the pump 26 is in open communication with the interior of the tank 10 by means of a hose or flexible conduit 36. It will be noted that the hose 36 is longer than necessary to provide a connection between the discharge opening 34 and the interior of the tank 10 and the purpose of this relatively long conduit 36 will be more apparent as the disclosure proceeds. The inlet opening 38 of the pump 26 is also provided with a flexible hose 41 which extends downwardly from the pump through an opening in the top 16 and into the recess 22. The hose 41 carries at the end thereof a tube 42 which is of such a small diameter as to be readily inserted through the existing measuring stick opening of an internal combustion engine. The eduction tube 42 is adapted

to extend to the lowermost part of the lubricating holding case as shown in Fig. 7 so that all of the liquid oil and sludge may be withdrawn through the measuring stick opening. Inasmuch as the lower end of the tube 42 is adapted to engage the bottom of the crank case, the lower end is notched or bevelled as illustrated at 44 to permit access of a lubricant and sludge to the interior of the tube and the hose line 41.

In carrying out the invention, the tube 42 is introduced through the measuring stick opening 43 as shown in Fig. 7 after the measuring stick 45 has been removed therefrom. The tube 42 is moved downwardly through the measuring stick opening until the lower end engages the bottom of the crank case and lowest portion of the sump 50. The motor 28 having previously been started and the pump 26 being in operation, the vacuum created in the hose line 41 will withdraw the oil and sludge from the crank case and deliver this liquid material through the line 36 into the tank 10. The connection between the hose or conduit 36 and the tank 10 is one of a quick change coupling type which includes a male part 46 as shown in Fig. 6 which is threaded into the top 16 of the tank and a detachable female part 47 which is connected to the tube or conduit 36. A quick change coupling is also provided between the tube 42 and the line 41. The apparatus includes a pipe 51 extending downwardly in the tank 10 to a point near the bottom thereof and this pipe is in open communication with the male part 46a of a quick change coupling. Thus when the tank 10 is filled with oil, the tube 42 may be readily removed from the hose 41 and this hose may then be connected to the pipe 51 and the male part 46a of the quick change coupling associated with the pipe 51. The hose 36 may be removed from its connection with the tank and this conduit may then be employed to discharge the contents of the tank to waste or a large receptacle. The pump 26 may therefore be employed to evacuate the oil from within the tank 10.

The apparatus includes a sheath 49 for storing a plurality of eduction tubes of various sizes and lengths so as to readily adapt the apparatus to engines having different sized openings and engines requiring eduction tubes of greater lengths. The sheath 49 is mounted at the lower end within the recess 22 and extends outwardly and upwardly therefrom and is attached to the top 16 by means of a bracket 53.

The pumping mechanism mounted on the top of the tank 10 is adapted to be enclosed within a hood shown generally at 56. The hood 56 is hinged at the lower rear edge thereof by means of a plurality of hinges 57. The hood 56 may be detachably retained in a closed position by means of a clasp assembly shown at 58. A handle 59 is provided for manual manipulation of the hood 56.

The apparatus includes means for indicating various conditions of operation of the apparatus and such indicating means in the embodiment illustrated are in the form of lamp assemblies carrying appropriate legends. These lamp assemblies are mounted in an inclined front portion 61 of the hood. The light 62 is provided for indicating that the liquid oil and sludge are being removed from the crank case. This lamp 62 as shown in Fig. 4 is energized when a vacuum operated switch diagrammatically illustrated at 63 is closed. This switch is encased within a relatively small housing 64 as shown in Fig. 3. The

switch 63 is actuated by a bellows 66 which is in open communication with the suction line 41. Thus when a pressure lower than atmospheric exists in the line 41, the bellows 66 will be partially collapsed as a result of the greater atmospheric pressure and the switch 63 will close to energize the lamp 62 and thereby indicate that liquid is being removed from the crank case. The housing 64 is accordingly not sealed so that atmospheric pressure will influence the operation of the bellows 66 and the switch 63.

The lamp 68 is energized when the switch 69 is closed. This switch 69 is mounted in the front inclined portion 61 of the hood and upon closure thereof the motor 28 is energized and starts. The lamp 68 is simultaneously energized and indicates that the motor is in operation. The signalling system includes means for indicating that the tank 10 is full and this indicating arrangement includes a lamp 71. The tank 10 is provided with a float operated switch diagrammatically represented at 72 and arranged within a casing 73. When the float 74 shown in Fig. 5 is raised, the switch 72 is closed to energize the lamp 71 and thereby indicate that the tank 10 is full. The apparatus is provided with electrical conductors 76 in the form of a flexible insulated cord connected to a male fitting 77 which may be plugged into an electrical outlet.

In carrying out the invention, the portable tank 10 which supports the pumping mechanism may be conveniently rolled on the casters or wheels 12 to a position adjacent a motor vehicle or an internal combustion engine. The flexible conductors 76 are preferably of such length as to extend to a convenient electrical outlet. Thereafter upon closure of the switch 69, the motor 28 is started and the pump 26 is set in operation. The indicator lamp 68 is energized to show that the motor and pump are in operation. The measuring stick is then removed from the measuring stick opening of the engine and the tube 42 may then be inserted through the measuring stick opening 46 into the crank case as shown in Fig. 7. The tube 42 is moved downwardly until the lower end thereof engages the lowermost part of the sump 50. The vacuum created within the hose line 41 will then cause the switch 63 to close whereby the lamp 62 is energized to indicate that the pumping operation has been initiated. The oil will be discharged through the conduit 36 and pass into the tank 10.

It is to be noted that some engines are provided with relative large openings for the measuring stick and fresh oil is introduced into the crank case through such openings. The tube 42 or a larger tube may be readily inserted through the oil introduction opening whereby the dirty oil may be withdrawn through an existing opening in the engine assembly. In some cases the eduction tube may be inserted through the breather opening.

It is desirable to remove the oil and sludge as quickly as possible and it is for this purpose that the pump arrangement is so designed as to remove the oil through the relatively small tube 42 within a period of approximately one minute. If desired, the crank case may be provided with flushing oil and this flushing material likewise removed through the tube 42. Under such circumstances it may be desirable to remove the hose 36 from coupled association with the tank 10 and to deliver the flushing oil into an auxiliary tank or receptacle. After repeated removal of oil from various engines, the tank 10 will be filled and the

float 74 will actuate the switch 72 to energize the lamp 71 and indicate that the tank 10 is full. The tank 10 may then be emptied by attaching the hose 41 to the coupling part 46a and the pump 26 may then be employed to withdraw the oil from the tank 10. During this pumping operation the conduit 36 is removed from connection with the tank 10 so as to discharge the oil into a storage receptacle.

10 It will be appreciated therefore that the present invention provides portable apparatus which may be employed for quickly removing the oil from the crank case of an internal combustion engine without the necessity of removing the drain plug in the bottom of the crank case and without the necessity of elevating the vehicle or positioning the motor car over a drain pit. It will be understood that the oil may be removed in a period of approximately one minute so that 15 fresh oil may be added to the crank case providing a complete oil change in a matter of a few minutes. While the invention has been described with reference to specific structural features and with respect to a particular type of 20 apparatus, it is understood that changes may be made in the various elements of the apparatus and such changes may be made without departing from the spirit and scope of the invention as 25 set forth in the appended claims.

30 I claim:

1. Apparatus for withdrawing oil from the crank case of an engine through the opening therein for the measuring stick comprising, a pump, means for operating said pump, conduit 35 means extending from the pump into the oil in the crank case through the measuring stick opening, vacuum responsive means associated with said conduit means, a switch operated by said vacuum responsive means, a signal lamp, a 40 source of electrical energy, and a circuit including said source and said switch and said lamp for indicating a pressure below atmospheric in said conduit means.

2. Apparatus for withdrawing oil from the 45 crank case of an engine through the opening therein normally accommodating the measuring stick comprising, a pump, means driving said pump, conduit means extending from the pump including a tube extending into the oil in the

50 crank case through the measuring stick opening, vacuum responsive means in open communication with said conduit means, a switch operated by said vacuum responsive means to close upon the development of a pressure below atmospheric 55 in said conduit means, and electrical signal means operated upon the closure of said switch to indicate that oil is being withdrawn from the crank case through the tube and the conduit means.

60 3. Apparatus for pumping oil from the crank case of an internal combustion engine comprising, a portable tank, a motor driven pump mounted on said tank having an inlet and a discharge outlet, a flexible conduit extending from the discharge outlet, a female coupling part secured to the end of said flexible conduit, a male coupling part communicating with said tank for receiving said female coupling part, a hose extending from the inlet of the pump, a female 65 coupling part carried by the end of said hose, a metal tube for introduction into the crank case of the engine through the measuring stick opening thereof, a male coupling part carried by the upper end of said tube for receiving the female 70 coupling part carried by the hose, a pipe within 75

said tank extending from a point near the bottom thereof and terminating at the top of the tank, and a male coupling part carried by said pipe exteriorly of the tank.

4. In apparatus for removing oil and sludge from the crank case of an internal combustion engine, a portable housing including a tank, a pump mounted on said housing, an electrical motor driving said pump, said pump having an inlet opening, a hose extending from the inlet opening, a female coupling part secured to the end of said hose in vacuum tight relationship, a metal tube adapted to extend to the bottom of the crank case through a measuring stick opening in the engine, a male coupling part carried by the upper end of said tube in vacuum tight relationship insertable in said female coupling part, said pump having a discharge outlet, a flexible conduit extending from the discharge outlet and of greater length than necessary to provide a direct connection with the tank and a female coupling part carried by the free end of said flexible conduit, a male coupling part secured to the tank and

in communication with the interior thereof adapted to detachably receive thereon the female coupling part at the end of said flexible conduit, a male coupling part attached to the tank for receiving thereon the female coupling part secured to the end of said hose, and said last-named male coupling part communicating with the bottom interior portion of the tank.

MICHAEL A. TABET.
